LOW-NOISE STATIC-DISCHARGE APPARATUS

Robert L. Tanner, Menlo Park, Calif.

Application March 15, 1957, Serial No. 646,465

12 Claims. (Cl. 343—899)

This invention relates to static-discharge systems and, more particularly, to an improvement in such systems wherein radio interference arriving from static discharge is minimized.

One of the causes of noise in radio receivers, especially those which are transported in aircraft, arises from the signals produced in antennas in response to corona discharges. Corona discharging apparatus is necessary in airplanes, and in order to minimize the pickup arising as a result, the discharge points are usually strategically placed as far from antenna locations as possible. This may serve to reduce the corona discharge noise somewhat, but it is still present. Also, attempts have been made without much success to find antistatic coatings. Presently favored are wick dischargers, but there is still considerable noise present.

An object of the present invention is to decouple the noise arising due to corona discharge.

Another object of the present invention is to provide a novel, static-discharge noise-decoupling arrangement.

Still another object of the present invention is to provide a static-discharge arrangement which can reduce the noise caused as a result of such discharge to a minimal value.

These and other objects of the invention are achieved in an arrangement whereby advantage is taken of the fact that an antenna is a reciprocal transducer. From this, it can be shown that when an antenna is excited with a radio-frequency voltage, the radio-frequency electric field strength existing at any point of space in the resulting field pattern is an indication of the strength of the signal which the antenna will receive from a noise source located at that point within the electric field. Thus, at points where no field is produced by an antenna-exciting voltage, no signal will be received by the antenna from signal sources placed at these points. Thus, to minimize noise due to discharges, the discharges should be induced to occur from points at which no field will be produced by a voltage at the antenna terminals. In accordance with this invention, means are provided for inducing discharges at null points within the field pattern of an antenna. This minimizes the noise due to corona or static discharges.

The novel features that are considered characteristic of this invention are set forth with particularity in the appended claims. The invention itself, both as to its organization and method of operation, as well as additional objects and advantages thereof, will best be understood from the following description when read in connection with the accompanying drawings, in which:

Figure 1 shows an isometric view of an embodiment of the invention;

Figure 2 shows in section the embodiment of the invention in an RF field configuration to assist in an understanding of this invention;

Figure 3 is another isometric view of another embodiment of this invention;

2

Figure 4 is a view in section of the embodiment of the invention shown in Figure 3; and

Figure 5 is a view illustrating the relative positions of a receiver, an antenna, and static decouplers in conjunction with an aircraft.

The description that follows will be directed to the application of the invention to aircraft, since corona discharge is most troublesome with aircraft. However, this is not to be construed as a limitation upon the invention, since it will be readily recognized by those skilled in the art that the principles explained and exemplified herein are applicable to receivers in any location where they pick up undesirable noises from corona discharges.

A radio-frequency voltage applied to antenna terminals 15 on an aircraft produces an electric field in space. In general, it can be said that such field tends to concentrate at the extremities of the aircraft and will be particularly concentrated at sharp points and edges at the extremities. In this respect, radio-frequency fields are 20 similar to the direct-current fields existing in space which induces corona discharges from such extremities. When such corona discharge occurs, an electrical disturbance propagates along the antenna of the receiver on the aircraft, resulting in current at the antenna terminals. This 25 terminal current can be said to be a measure of the radio noise produced by the discharge.

A corona-discharge current is very localized in space, occupying only a very small volume. Considered as a function of time, such currents flow as very sharp pulses.

30 Each of these sharp pulses has significant components at relatively high radio frequencies. It is known that an antenna is a reciprocal device. From this, it can be shown that the noise signal which arises in the antenna from a corona pulse is proportional to the strength of 35 the electric field created at the point where the corona discharge takes place as the result of applying a voltage to the antenna terminals. It was previously pointed out that the radio field tends to concentrate at extremities in sharp points in a manner similar to the direct-current field producing the discharge. In other words, the discharges tend to occur at just those points where coupling to the antenna is maximum.

Under normal circumstances, if the configuration of 40 the radio-frequency field which measures the coupling is examined, it will be found that if only a small region is considered (about a wingtip, for example), the shape of the radio-frequency field is the same as the direct-current field that would exist at the point if the entire aircraft were raised to a high potential. Where the direct-current fields are high, leading to discharges, the radio-frequency fields are also high, leading to high coupling. Therefore, 45 in order to effect decoupling, it is necessary to exploit the basic differences between the radio-frequency and direct-current fields in such a way as to allow high direct-current or static fields to occur at points where the radio-frequency field is small. This decoupling is accomplished by this invention.

Referring now to Figure 1, there is shown one embodiment of the invention. The wingtip 10 of an airplane 50 has attached thereto a rope 12, which may either be fabricated of a material having a high resistance or be an insulating material coated with a high-resistance coating. The rope is attached to what may be termed a tubular electrode 14. This includes a cross-supporting 55 conductive member 16, to which the rope is attached, and which itself is attached to the cylinder 18. Around the equator of the cylinder are a plurality of discharge elements or points 20, which are made from tungsten. Use is made of the fact that, to the static or direct-current field, a distributed high resistance appears like a conductor, whereas the radio-frequency field is relatively unperturbed by it. Thus, the conducting body, suspended

at the end of the distributed resistance 12, appears isolated to the radio-frequency field while appearing to the static field as a projection from the wing.

This may better be seen in Figure 2, wherein the embodiment of the invention is shown in section. If a radio-frequency voltage is applied to the antenna terminals, creating a radio-frequency field in the vicinity of the wingtip, the impedance of the resistance rope 12 would be extremely high relative to the reactance of the space between the wingtip and the electrode, so that the electrode 10 appears isolated as far as the radio frequency field is concerned. The radio-frequency field configuration 22 has the appearance represented by the dashed lines, which may be termed the field lines. As indicated by the figure, it will be seen that there are as many lines leaving the isolated body or electrode 14 as enter it. This means that at some point on the body lines neither enter nor leave, which signifies that at this point the RF coupling field is zero. Therefore, discharges occurring from these points situated at the null point of the radio field do not couple appreciably to the receiver antenna. Further, it is well known to those acquainted with the art that at the tips 20 a concentration of the direct-current field will occur so that these points go into corona easily.

In Figures 1 and 2, the conducting cylinder is shown at the end of a resistive rope. The conducting cylinder may be replaced by a sphere, or, indeed, may be any shape, provided that the conducting body is isolated with respect to the radio-frequency field of the antenna of concern. The length of the rope is immaterial, provided it has a sufficient distributed resistance to provide the required radio-frequency field isolation.

It is evident that the principles described above are equally applicable to both a two-dimensional field geometry, as well as to a three-dimensional field geometry. Thus, if preferred, a flush-mounted permanent-discharger installation may be employed. Figures 3 and 4 show such an embodiment of the invention. The metal at the surfaces near and extending to the tips of the wings and other surfaces may be replaced by some form of plastic structure 30, such as a combination of structural Fiberglas and resin with a metal cylinder embedded in the tips, or preferably some form of a metal overlay 32. The plastic structure may be rendered slightly conductive by the addition of a lampblack to the resin before layup, or by coating with a resistive paint. The wingtip metal overlay has attached thereto a plurality of sharp metal discharge points 34. The location of these discharge points is along the line where the radio-frequency field is zero. The trailing edge 36 of the metal overlay is given a sufficiently large radius to insure that there is no tendency for discharges to occur there, these discharges should only occur at the points. The extent of the plastic structure must be, as in the case of the resistive rope, sufficient to provide the required radio-field isolation for the metal overlay. The location for the discharge may either be calculated or measured using electrolytic tank techniques.

The embodiments of the invention described, in addition to producing very low noise, also have the advantage that they can be built to have almost any desired discharge capacity. The current from any discharger is limited by space charge. Current leaving the discharger is carried away as ions. These move with finite speed, which in an aircraft in flight is essentially the slipstream velocity. There is, however, a components of motion due to the electric field. The fact that the ions move at finite speed means that there is always a cloud of ions surrounding the discharge point, and these ions have the same sign as the charge which is attempting to escape. The effect of this charge cloud is to diminish the field at the point, thereby limiting the amount of charge leaving the point. In the flush-mounted discharger, shown in Figures 3 and 4, the row of points acts like a line source of ions, rather than a point source. The space

charge is more widely distributed in space, so that its shielding effect is less. In addition to this basic advantage, the discharger section can be made as long as necessary without compromising the aerodynamic characteristics of the aircraft. In this way, dischargers of capacity adequate to discharge even large, high-speed aircraft can be built. Figure 5 illustrates the relative locations of a receiver, an antenna, and static dischargers, in accordance with this invention, on the body of an airplane 38. Three receivers 40, 42, 44 (represented by rectangles) are shown, positioned at the forward end of the airplane 38. One of these 40 is used in conjunction with a flush-mounted automatic direction finder 46, which has its sense antenna (not shown) recessed in the belly of the aircraft. The second and third of the receivers 42, 44 are connected to their antennas (respectively represented by rectangles 48, 50) which are usually located under a plastic cover on the tip of the vertical stabilizers 52 of the airplane. The antenna 48 represents one which is employed as the Loran antenna, and the antenna 50 may be employed as the high-frequency receiving antenna. The locations of the embodiments of the invention are represented by the groups of lines 54, 56, 58, 60, 62, which extend respectively from the outer tips of the wings, the outer tips of the horizontal stabilizers, and the top of the vertical stabilizer.

Accordingly, there has been shown and described above a novel, useful, unique, and simple arrangement for minimizing the noise arising as a result of corona or static discharges in an antenna by establishing the apparatus for discharging corona at null points within the radio-frequency field of the antenna yet preserving the connection of the apparatus with the surfaces to be protected against corona discharges. Although the embodiments of the invention have been described in connection with an aircraft, it will be understood that the invention may also take other forms and can be used to minimize corona noise caused at stationary structures or on other vehicles or devices. These other uses and forms are also intended to be included within the spirit of this invention and the scope of the claims appended herein.

I claim:

1. In a system of the type wherein noise from corona discharges are detected at the terminals of an antenna, an improved noise minimizing arrangement comprising means for discharging corona, and means for supporting said means for discharging corona at a null point within the radio-frequency field of the antenna.

2. In a system of the type wherein noise from corona discharges caused by a direct-current field are detected at the terminals of an antenna, an improved noise minimizing arrangement comprising a corona discharge element, and means for supporting said corona discharge element at a null point within the radio-frequency field of said antenna yet still within the direct-current field.

3. In a system as recited in claim 2 wherein said means for supporting said corona discharge element at a null point includes a conductive body and a resistive element connected to said body.

4. A static-discharge noise-decoupling device for a structure including a receiver having an antenna, said structure having surface tips at which corona discharges occur comprising a body having a conductive surface, a plurality of discharge points mounted at radio-frequency field null points on the surface of said body and distributed resistance means for holding said body spaced from said surface tips.

5. A static-discharge noise-decoupling device for a structure having surface tips at which corona discharges occur as recited in claim 4 wherein said body is a metal cylinder, and said means for holding said body is a resistive rope having one end attached to said surface tips and the other end to said metal cylinder.

6. A static-discharge noise-decoupling device for a structure as recited in claim 4 wherein said distributed

resistance comprises plastic material and means for rendering said plastic material conductive.

7. A device for decoupling corona discharge noise from the antenna of a receiver carried on a vehicle having surface tips at which corona discharges occur comprising a distributed resistance means including plastic sheets extending from said vehicle surfaces to form said tips, means for rendering said plastic sheets resistive, corona discharge means supported by said distributed resistance means including a metal overlay for said tips, and a plurality of corona discharge elements positioned along said metal overlay said plastic sheets extending from said vehicle surface a sufficient distance to place said corona discharge elements in the null region of the radio field of said antenna.

8. A static-discharge noise-decoupling device for an aircraft carrying a receiver antenna and having wingtip surfaces at which corona discharges occur comprising a metal body having a circular surface, a plurality of corona discharge points mounted symmetrically over said circular surface, and a resistive rope having one end attached to said tip surfaces and the other end to said metal body, the length of said rope being sufficient to maintain said metal body at the null point within the radio-frequency field of said receiver antenna.

9. In an aircraft carrying a receiver antenna and having wingtips subject to corona discharges, an improved static discharge noise-decoupling arrangement comprising distributed resistance means at said wingtips including plastic sheets extending from said wingtips toward the wing surfaces, means rendering said plastic sheets resis-

tive, a conductive metal termination for said wingtips, and a plurality of corona discharge points supported from said conductive metal termination along a null region of the radio-frequency field of said antenna.

10. In an aircraft carrying a receiver antenna as recited in claim 9 wherein said conductive metal termination for said wingtips includes a metal overlay over said plastic sheets.

11. The method of decoupling noise from a receiver having an antenna which picks up said noise from corona discharges caused by a direct-current field comprising establishing a null region of said antenna radio field within said direct-current field, and establishing said corona discharge at said null region.

12. In a vehicle carrying a receiver having an antenna which picks up noise from corona discharge points the method of decoupling said noise comprising establishing a null region of said antenna radio field, and resistively supporting said corona discharge points within said null region from said vehicle.
